UNITED STATES PATENT OFFICE.

HENRY J. BROWER, OF BROOKLYN, AND FRANK B. WOOD, OF NEW YORK,
N. Y., ASSIGNORS OF ONE-FOURTH TO BENJAMIN E. VALENTINE, OF
BROOKLYN, NEW YORK.

AUTOMATIC ELECTRIC SIGNALING APPARATUS.

SPECIFICATION forming part of Letters Patent No. 252,353, dated January 17, 1882.

Application filed April 27, 1881. (No model.)

To all whom it may concern:

Be it known that we, HENRY J. BROWER, of the city of Brooklyn, New York, and FRANK B. WOOD, of the city of New York, N. Y., have invented a new and useful System of Automatic Electric Signaling; and we do hereby declare that the following specification, taken in connection with the drawing annexed to and forming part of the same, contains a full, clear, and exact description of our said invention, sufficient to enable those skilled in the art to which it pertains to construct and operate the same.

Our invention has particular reference to the systems of electrical signaling now in use by the various district-telegraph companies of our large cities and the systems of fire-alarm telegraphs, though the same may be applied and found useful in many other cases. In the systems above mentioned, as is well-known, a signal is given by causing the revolution, at any given station or point upon the line of electrical communication, of a notched wheel or its equivalent, which breaks or opens and closes the electrical circuit. The signal is received on what is known as a "register" in the main or central office of the line, and by an impression upon a moving ribbon of paper or the ringing of a bell by a magnet, or both, the signal is announced, showing by the number of strokes on the bell, or by the impression upon the paper, the peculiar number or designation of the station whence the signal is sent and the character of the signal.

It frequently happens that from divers causes—*e. g.*, atmospheric influences, accidents to the wires, clogging, or defects in the working of the local apparatus, &c.—a signal which is sent from a signal-box is not received or registered at the central office. In some cases—*e. g.*, where a signal for "fire," or to call "police" or a "physician"—is sent, it is of the utmost importance for the sender of the message to be assured that its reception has not been delayed or interfered with; for if aware that any defect has prevented the proper transmission of his signal, other means can be at once adopted for conveying the information desired; while on the other hand, if deceived by the fancied security afforded by a defective connection, val-

uable time would be lost before the sender of 50 the signal ascertained, by a failure of his signal to elicit any action on the part of the central office, that it had been prevented from reaching them. This feature of assuring the signaler of the proper reception of his signal 55 has been deemed so important that in some of the central offices a person has been stationed to signal back, by reversing the current, &c., the announcement that the message is received.

The first object of our invention is to provide a means by which, when a signal is sent from a signal-box to the central station a response-signal will be automatically returned to the precise signal box from which the message originated, and to no other, thus assuring the sender of the due receipt of his signal 60 at the proper office.

In the drawing, A represents a signal-box placed upon the main circuit at a distance from the central office.

At Z is shown register mechanism located at the central office.

W is the main battery, Y the local battery; and R is the relay to close local circuit and operate the register through M².

M² is a coil and magnet, which, by its armature L, operates a lever whose end Q stops the train of the register when the local circuit is broken and releases the train when the local circuit is closed, allowing one complete revolution of the wheel (and all the other wheels on the shaft or axle J) whenever the end Q is raised out of the notch on the wheel. M² may be the same magnet which is used in the ordinary register for working the recording-pen. 80 The main circuit is from the signal-box A, along the line E², through the other signal-boxes on the line, (shown at A² A³, &c.,) through the main battery W, into the register, through the contact-spring G', out of the register, through the contact-spring G², over the line E⁴, through the relay R, and back to the signal-box over the line E', or vice versa.

The signal-box A is of any suitable construction, such as is in common use, B being the 95 signal-wheel, and C' the circuit-breaker, which, by means of the notches a a or their equivalent, breaks the circuit, the system in the

present case being supposed to be what is known as the "closed circuit." So long as the circuit-breaker C' rests on the wheel B the signal-box is in circuit, D' being the wire which makes the connection between the sections of the main line E' E². The circuit in the ordinary movements of the signal-box is along E', over the wire D' and breaker C', through the wheel B, and back through the line E², or vice versa.

At Z is shown the operative part of the register used as part of this invention. The registers ordinarily used in telegraph-offices are constructed to move automatically by a weight or spring, which, when released by the action of the local current, causes a ribbon of paper to be moved along under the impinging point of a pen or other marking apparatus.

The train-movement (shown at Z) which forms part of our invention, may be used independently of the ordinary register, or may be added to such register.

T represents a barrel containing a coiled spring for actuating, in the ordinary manner, a train of wheels by the cog-wheel K', attached to the barrel. The teeth of K' gear into a pinion, H, which is fixed on the shaft or axle J.

K² is a gear-wheel on the same shaft J; and H² K³ H³ are a series of gear-wheels and pinions terminating in an escapement-wheel, O.

P is an escapement-lever, which controls the movements of the escapement-wheel O, and which has upon its lever-arm an adjustable weight, n. By means of the weight n the escapement can be adjusted so as to vary and regulate the speed of revolution of the shaft J and the wheels which revolve with it. The adjustment should be so made that the wheels on J shall revolve at the same rate of speed and occupy the same time in a revolution as the signal-wheel B in the box A.

F F² S² together are a series of wheels, or a cylinder with different diameters upon the shaft J, which, as before stated, revolve at the same rate of speed as the signal-wheel B, and which are always in the main circuit by the scraping connection formed by the contact-spring G² upon the surface F². The circuit at the register is completed by the contact-spring G', which bears on the surface of F, keeping the circuit closed at all times, except when the notches f f break the circuit momentarily by passing under the end of the contact-spring G'. These notches are placed on that quarter of the wheel F which is the last to pass, during its revolution, under the contact-spring G', so that the main circuit will be broken just before the completion of the revolution of the register-wheel F.

Upon the signal-wheel B in the box A, at that portion of its surface which is in contact with the spring C' during the last quarter of its revolution, the surface is cut away or insulated, as shown at b b', so that during the last quarter of the revolution of B the contact-spring C' opens the circuit after the signal is

sent. At one side of the same portion of the signal-wheel B is attached a section of a wheel, S, preferably joining the segment of a circle of larger diameter than the wheel B. The object of S is to form a circuit or contact for the wheel B with a second contact-spring or circuit-breaker, C², during that period of time when the contact-spring C' is thrown out of circuit at b b'. The effect of the last quarter of revolution of said wheel B is to throw the line D' out of circuit as soon as the signal has been sent over it, and to throw the magnet M (which operates the bell N by means of the well-known armature mechanism) into circuit through the wire D², this circuit lasting until the wheel B has completed its revolution to the point t² of the segment S, at which point the contact-spring C² leaves the segment S, and the contact-spring C' again comes in contact with the surface of the signal-wheel B at b', thus restoring the circuit through the line D' and "cutting out" the temporary circuit through D².

S² is a segment, similar to S, connected with the cylinder or wheel F at the side of F², which, during the last quarter of revolution of the shaft J and wheel F, puts in circuit the line E³, as hereinafter described.

It is obvious that as the wheel F in the register revolves at the same speed as the wheel B in the signal-box, the segment of F containing the notches f f, which break the circuit, will be presented to the scraper or circuit-breaker G' at the same time that the section S' in the signal-box is presented to the circuit-breaker C², and at the same time that C' is thrown out of connection, and C², with its magnet and bell, thrown in circuit. As soon, therefore, as the signal has been given by the revolving signal-wheel B through C', and received on the register by the ordinary and well-known means, a new circuit will be formed by the continuing revolution of the wheel B through S, C², D² and the magnet M, and the bell N will be sounded once at the moment of forming the new circuit by the contact of C² at the point t², and again as each of the notches f f on the wheel F breaks and closes the circuit by means of G'. This is done automatically, and after this return signal is given the completion of the revolution of the wheels B and F restores the original circuit ready for further direct signals.

The next part of our invention relates to a method of cutting out the relay-magnet R.

It is a fact well known to those familiar with electrical telegraphy that if there are two or more of the ordinary magnets with their armatures upon the same line and in circuit, in order to have all of them operate under a given electrical current the power or resistance of the respective magnets must be similar. Thus, if the magnet in the relay R is of one hundred ohms, the magnet at the bell N must be also of about one hundred ohms; otherwise only one of them—viz., the stronger—would operate when in circuit. The magnet usually used and

required at the register-relay R is of comparatively large resistance, or high number of ohms. If a magnet of like number of ohms was placed at M, the expense would be unnecessarily great, 5 for our invention contemplates a magnet and bell at every signal-box for return signals. To secure the ringing of the bell N only a small magnet of a few ohms would be necessary were it not for the more powerful magnet in the relay R, which has to be equalized. This part 10 of our invention therefore consists of means by which the magnet of the relay R is cut out of the circuit (and this may be done automatically) while the return signal is given, thus 15 avoiding the effect of its powerful magnet, and allowing a small magnet, M, of fewer ohms resistance, to ring the bell N.

In the drawing, E' is the main line, on which the relay is interposed between the register, 20 with its wheel F, and the signal-box, with its wheel B. The course of the current, under the ordinary condition of affairs is from the signal-box at X, along the wire E', through the standard V', and thence through the relay R to the 25 register by the line E⁴. As the electric current always takes the shortest course, however, between two points connected, if a direct connection is made between the register and the standard V' the current will pass through the 30 latter wire, and the relay will be cut out or not brought into play, and therefore the effect of its powerful magnet will be avoided.

E³ is a wire, one end of which is connected with the standard V' and the other end is connected with a circuit breaker or scraper G³.

S² is a piece of metal similar to S upon the signal-wheel B, but placed upon the last quarter of revolution of the register-wheel F. During the period of time while the signal 40 from B is being received on the register the circuit-breaker G³ is not in contact with the wheel F, but during the last quarter of the latter's revolution, and after the signal from B is received and announced the section S² comes in contact with the end of the circuit-breaker G³, thereby putting the wire E³ in circuit, by which the current will flow directly to the signal-wheel B through the point V', thus cutting out the magnet of the relay, and 45 enabling the cheaper and feeble magnet M in the signal-box to operate the bell N. Upon 50

the completion of the revolution of the wheel F the circuit-breaker G³ is automatically thrown out of circuit by passing from the end of the section S². By this means an answering return signal, by the ringing of a bell, can be automatically given upon the receipt of the direct signal at the station to which it is sent, and the expense of the apparatus required to 55 accomplish this is but small.

It is obvious that with an open-circuit system the same invention may be utilized by making changes in the details of the parts.

Having thus described our invention, what we claim, and desire to secure by Letters Patent, is—

1. The combination of the revolving wheel and contact-surfaces F and F², a register for recording electric signals, an electric circuit, of which the signal-box A, for automatically 70 breaking the circuit, forms a part, and with the simultaneously-revolving wheel and contact-surfaces B and S, located in said signal-box, and mechanism for switching the circuit through the magnet M, and with the contact-springs and circuit-breakers, forming part of the above-named electric circuit, substantially 75 as described, for the purpose of automatically announcing a return signal.

2. The combination, with a revolving contact-surface, F, for sending a return signal, of the electric circuit of which the signal-box A forms a part, the relay-magnet R, revolving contact-segment S², and intervening connections for automatically cutting the magnet R 80 out of circuit temporarily and restoring it to circuit, substantially as and for the purposes specified.

3. The within-described means for automatically cutting out and restoring the relay-magnet R, from and to an electric circuit, consisting of the combination of the revolving contact-surfaces F² and S² with the contact-spring G², and circuit-breaker G³, battery W, lines E² and E' of the circuit, and line E³ for short-circuiting, substantially as set forth.
